UNITED STATES PATENT OFFICE.

WILLIAM F. ROHRBACHER, OF PORTLAND, OREGON, ASSIGNOR OF ONE-HALF TO
EDWARD J. ROHRBACHER, OF PORTLAND, OREGON.

ENGINE-STARTER.

1,175,994.

Specification of Letters Patent. Patented Mar. 21, 1916.

Application filed April 25, 1911. Serial No. 623,209.

To all whom it may concern:

Be it known that I, WILLIAM F. ROHRBACHER, a citizen of the United States, residing at Portland, in the county of Multnomah and State of Oregon, have invented a new and useful Engine- Starter, of which the following is a specification.

The device forming the subject matter of this application, is adapted to be employed for giving an initial rotation to the shafts of internal combustion engines, to effect a starting of the same.

The primary object of the invention is to provide fluid-pressure actuated means for imparting a rotation to the shaft of an internal combustion engine.

A further object of the invention is to provide a fluid-pressure actuated means, working with resilient means, to effect reverse rotations of an element, adapted to have clutch and release connection with the shaft of an internal combustion engine, to effect a starting thereof.

Other and further objects will be made manifest hereinafter, as the description of the invention progresses.

With the foregoing and other objects in view which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

In the drawings.—Figure 1 is a sectional plan of the device; Fig. 2 is a sectional plan of the clutch and release mechanism, whereby by rotation is imparted to the engine shaft from the fluid pressure mechanism; Fig. 3 is an elevation of one of the elements which, forming a part of the structure shown in Fig. 2, serves to actuate the engine shaft; Fig. 4 is a plan of the spring whereby the parts are returned to normal positions, after the engine shaft has been actuated; Fig. 5 is a sectional elevation of the valve whereby the fluid pressure portion of the apparatus is actuated; and Fig. 6 is a sectional elevation of an auxiliary starting frame which may be employed in connection with the invention.

In the drawings, a portion of the supporting structure is shown, and denoted by the

numeral 1. The device forming the subject matter of this application, is adapted to be employed upon automobiles, air-ships, motor boats, and elsewhere, where a hydro-carbon engine may be employed, and therefore 60 the numeral 1 may be taken to indicate any portion of any one of the structures above referred to.

The engine is denoted by the numeral 2, the engine shaft by the numeral 3, the fly 65 wheel by the numeral 4, and the radiator by the numeral 5.

The invention further includes a tank 6, adapted to contain fluid under pressure. The manner in which fluid pressure is stored 70 within the tank 6, is of no particular consequence, and fluid pressure may be supplied to the tank 6 in any desired manner. In the present instance, however, in order to present an operative structure, an air pump 7 is 75 shown, the shaft of which carries a friction wheel 8, adapted to bear against the fly-wheel 4. Communication is established between the air-pump 7 and the tank 6, by means of a pipe 9.

A device is provided, whereby the operator may control the fluid pressure within the tank 6, to actuate certain mechanisms hereinafter to be described. This device, most clearly shown in Fig. 5, comprises a 85 tubular casing 10, provided with a depending neck 11, rotatable in a head 12, formed at one end of an arm 14, the arm 14 being secured to any portion of the supporting structure. The casing 10, therefore, may be 90 turned about at an angle in the head 12, and in order to lock the casing 10 at its adjusted angle, a nut 17 is threaded upon the lower portion of the neck 11. The lower end of the neck 11 carries a removable nipple 15, 95 adapted to receive one end of a connection 16 (see Fig. 1) the other end of the connection 16 entering the tank 6.

Fixed to and upstanding from the casing 10, is a standard 18, upon which is fulcrumed, intermediate its ends, a lever 19, to one end of which is pivoted a rod 20, carrying a foot plate 21.

That end of the lever 19 to which the rod 20 is attached, is positioned above, and is 105 adapted to engage, the upper end of a stem 22, slidable in a neck 23, fashioned upon the casing 10, the leakage of the fluid pressure about the stem 22 being prevented by means of a suitable packing gland 24, threaded into 110

the neck 23. That end of the lever which carries the rod 20 is normally maintained upheld by means of a compression spring 25, the upper end of which bears against the lever 19, the lower end of which surrounds the neck 23, and bears against the casing 10. The lower end of the stem 22 passes through a port 26 formed in the lower portion of the casing 10, and communicating with the interior of the neck 11. About the port 26 there is a rib 27, projecting into the neck 11, the rib 27 being adapted to be engaged by a packing ring 28, seated in the upper face of a head 29, secured to the lower end of the stem 22. The head 29 is normally maintained uplifted, so as to close the port 26, by means of a compression spring 30, the upper end of which bears against the head 29, the lower end of the spring 30 bearing against the removable nipple 15.

That end of the lever 19 which is remote from the rod 20, is positioned above, and is adapted to engage, a stem 31, slidably in a lug 32, fashioned upon the casing 10. To the lower end of the stem 31 is attached a head 33, carrying in its upper surface, a packing ring 34, adapted to engage a rib 35, fashioned upon the casing 10, about a chamber 36 in the lug 32, there being ports 37, extending through the lug 32. The stem 31 is prolonged below the head 33, to form an extension 31', adapted to register in an opening 40, formed in a plug 39, inserted into a nipple 38, forming a part of the casing 10. The head 33 is adapted to be lifted, so as to close the ports 37, by means of a spring 41, the upper end of which bears against the head 33, the lower end of the spring 41 bearing against the lug 39, and surrounding the extension 31'. Compared with the spring 25, the spring 41 is relatively weak.

At its extremity, the casing 10 may be provided with a removable nipple 42, adapted to engage one end of a pipe 43 (see Fig. 1) the pipe 43 entering a head 44, upon the forward end of a cylinder 45, supported in frame-carried brackets 46. The head 44 carries a suitable packing gland 47, in which reciprocates a piston rod 48, carrying, within the cylinder 45, a cylinder head comprising a back plate 49, a resilient, cup-shaped disk 50, a front plate 51, and securing nuts 52. In the rear head 53 of the cylinder 45 there are ports 54, having functions which will be described hereinafter. Adjacent its free end, the piston rod 48 carries a fixed shoulder 55, backed by a resilient buffer 56.

Secured to the free end of the piston rod 48, as shown at 57, is one end of a flexible member 58, carried over a flanged sheave 59, journaled for rotation in a frame-supported bracket 60. The flexible member 58 is carried about the periphery of a flanged primary wheel 61, mounted for free rotation upon the engine shaft 3. The primary

wheel 61 is equipped with a rearwardly extended hub 62, to which is secured, as shown at 63, a spiral spring 64, one end of which is carried by an attaching member 65, inserted into any suitable portion 66 of the frame 1. The primary wheel 61 is centrally open, and carries, in its centrally open portion, a ratchet 67, which may be fashioned integrally with the primary wheel 61. This ratchet 67 is adapted to be engaged by a series of pawls 68, pivoted in a centrally open secondary wheel 69, the wheel 69 being telescoped within the wheel 61. The wheel 69 is secured to the engine shaft 3 in any desired manner. In the present instance, the wheel 69 is secured to the engine shaft 3 through the medium of a key 100.

The wheels 61 and 69, and the spring 64 are housed beneath a casing 70, the casing 70 having a laterally extended shield 71, adapted to extend over the sheave 59 and over the flexible member 58. The casing 70 terminates in a neck 72, upon which may be inserted a spring retained cap 73, housing the end of the engine shaft 3. That end of the engine shaft which is adjacent the cap 73, is centrally open, and into the end of the shaft 3 is threaded a plug 74.

The invention further includes an auxiliary starting crank, shown in Fig. 6 and denoted by the numeral 75. This starting crank 75 carries a latch member 76, actuated by a spring 77.

Presupposing that the tank 6 is charged with air under pressure, and that the parts are positioned as shown in Figs. 1 and 5, the operation of the device is as follows: If the foot of the operator be placed upon the foot plate 21, the lever 19 will be depressed, engaging the stem 22, and withdrawing the head 29 from the port 26, the spring 30 being put under tension. This tilting of the lever 19 will free the lever from the stem 31, whereupon the spring 41 will elevate the head 33, and close the ports 37. Under such circumstances, the fluid pressure from the tank 6 will traverse the connection 16, the nipple 15, and the neck 11, the port 26, the casing 10, the nipple 42, the pipe 43, and thence enter the cylinder 45, in advance of the piston head therein. Under such circumstances, the piston head will be forced rearwardly in the direction of the arrow A in Fig. 1, the air in the cylinder 45 which is to the rear of the piston head, passing out through the ports 54. When the piston head is thus actuated, the rod 48 will exert a pull upon the flexible member 58, the same passing over the sheave 59, and rotating the primary wheel 61, the ratchet 67 of which will engage the pawls 68 of the secondary wheel 69, rotating the secondary wheel 69, and with it, the engine shaft 3, to which the secondary wheel 69 is attached. During this operation, the spiral spring 64 will be put

under tension. As soon as the shaft 3 begins to rotate, under impulse from the engine, the pawls 68 will fly outwardly, so that they no longer engage with the ratchet 67.

- 5 After the operation hereinbefore described has been completed, the foot of the operator is removed from the foot plate 21. Under such circumstances, the spring 25 will restore the parts to the positions shown in
 10 Fig. 5, the inlet port 26 being closed, and the outlet ports 37 being opened. The air which is imprisoned in the cylinder 45, in front of the piston head, will bleed back through the pipe 43 into the casing 10, and thence
 15 outwardly through the ports 37. When the fluid pressure is thus reduced, in advance of the piston head in the cylinder head 45, the spring 64 will rotate the loose wheel 61, and wrap the flexible member 58 about the wheel
 20 61, the piston rod being drawn forwardly, and the piston head within the cylinder 5, being restored again to the position shown in Fig. 1. It is to be noted that before the lever 19 engages the stem 22, the stem 31 will
 25 be set free, and therefore, the ports 37 will close before the ports 26 open. Thus, in operation, there is no waste of fluid pressure through the ports 37. Conversely, the port 26 will be closed before the ports 37 are
 30 opened, and therefore the fluid pressure proceeding from the tank 6, will not oppose the fluid pressure proceeding, as an exhaust, from the cylinder 45.

The operation hereinbefore described, for
 35 imparting rotation to the engine shaft 3, may be repeated as long as there is any fluid pressure remaining in the tank 6.

When the piston head in the cylinder 45 moves in the direction of the arrow A, the
 40 buffer 56 will engage with the gland 47, and since this buffer 56 is resilient, there will be no appreciable jar in the operation of the apparatus.

By rotating the plug 74 in the end of the
 45 engine shaft 3, a lubricant may be forced through the center of the shaft 3, for the purpose of oiling the loose primary wheel 61.

It will be understood that the cap 73 may be removed, whereupon the lever 75 may be
 50 placed upon the end of the engine shaft, a rotation being imparted to the engine shaft manually, when desired, instead of employing the fluid-pressure actuated apparatus hereinbefore described.

55 When the lever 75 is used, the latch 76 will engage with a longitudinal groove in

the engine shaft 3, as is common and well known in the art.

The spring 64, it is to be noted, tapers from its inner to its outer end. Owing to
 60 this construction, an even spring-tension will be secured, even under different degrees of winding.

When the piston moves in the direction of the arrow A under fluid pressure, the buffer
 65 56 strikes against the gland on the forward end of the cylinder and thus the movement of the piston in one direction is limited. When the movement of the piston in the direction of the arrow A thus is suddenly
 70 arrested, the flexible element 58 loosens momentarily and tends to jump off the sheave 59. Should the flexible element thus be loosened from the sheave, the outer end of the extension 71 (which acts as a guard) 75 will return the flexible element to the sheave 59. In addition to the foregoing, the outer end of the extension 71 acts as a protection for the sheave 59 when the latter is rotated.

Having thus described the invention, what
 80 is claimed is:—

In an engine starter, a shaft, a wheel rotatable thereon and having a hub and rim projecting in opposite directions, a second wheel disposed upon the shaft within the
 85 rim of the first mentioned wheel and having a hub and rim projecting in opposite directions, the rim of the second mentioned wheel projecting toward and closely adjacent the first mentioned wheel, a flexible 90 element wound upon the rim of the first mentioned wheel and adapted to be unwound for rotating said wheel, the hub of the second mentioned wheel being secured to the shaft, a spiral spring arranged adjacent the
 95 outer side of the first mentioned wheel and having its inner end secured to the hub of said wheel, the outer end of said spring being anchored, the first mentioned wheel having a ratchet projecting toward and adjacent the second mentioned wheel, and pawls pivoted to the inner side of the second mentioned wheel and coöperable with the ratchet.

In testimony that I claim the foregoing as
 100 my own, I have hereto affixed my signature in the presence of two witnesses.

WILLIAM F. ROHRBACHER.
